UNITED STATES PATENT OFFICE.

WALTER H. COTTON, OF CHICAGO, ILLINOIS, ASSIGNOR TO UNION DRAFT GEAR COMPANY, OF CHICAGO, ILLINOIS, A CORPORATION OF DELAWARE.

DRAFT GEAR.

Application filed March 23, 1925. Serial No. 17,613.

This invention relates to improvements in shock absorbers, and more particularly to draft gears for railway cars.

One of the objects of the invention is the provision of a new and improved type of gear casing for housing the shock absorbing mechanism.

Another object of the invention is the provision of new and improved means for mounting the draft gear.

Other objects of my invention are to provide a draft gear embodying a practical application of the horizontal draft principle, which is sturdy and cheap in construction, reliable in operation, easily assembled and inspected, and one which is adapted for use in any type of draft gear attachment having a pocket large enough to accommodate the same, and is readily removable for repairs.

Another and more specific object of my invention is to provide a draft gear comprising two opposed interlocking hollow casings slidably mounted, and one which is constructed in such manner as to provide abutments for the draft springs therein on the opposite interlocked portions thereof.

Other and further objects of my invention will appear from an inspection of the accompanying drawings, wherein like reference numerals have been used to designate like parts, and wherein:

Fig. 1 is a view partly in plan and partly in section, showing the gear applied to a car, and in normal position;

Fig. 2 is a longitudinal vertical section of the gear under full compression, some of the parts of the gear and car frame being shown in elevation;

Fig. 3 is a view taken along the line 3—3 of Fig. 2;

Fig. 4 is a perspective view of a casing employed in the gear;

Fig. 5 is a similar view from the opposite end of the same casing;

Fig. 6 is a perspective view of a locking pin for the casings.

On the drawing the reference characters 10 and 11 designate the center sills of a railway car to which is secured the abutment member 12. The sills are provided with alined openings or elongated slots 13. Check plates 14 and 15 having elongated slots 16 are mounted alongside the sills 10 and 11. The slots 16 may be of substan-

tially the same length. The plates may be and preferably are provided with flanges 19 extending about the margins of the slots 16, which are adapted to engage the slots 13 in the sills for holding the check plates 15 in position and for forming broad bearing surfaces for the keys as will presently appear.

A pair of draft links 21 and 22 having slots 23, 24 and 25 are mounted between the sills as by means of keys 26, 27, 28, which extend through the corresponding slots in said check plates and draft links. The forward slot 16 is of sufficient length to permit the movement of the key 26 forward or backward as the gear is compressed, respectively, by stresses of draft or buff. The forward slot 23 is shorter, as the key 26, while free to move backward therein under buffing stresses, carries forward with it, under stresses of draft, the link 24, 25, communicating through them forward movement to the key 28 and through it to the block 22. The slot 24 and the associated slot 16 are of such length as to permit movement of the key 27 backward under stresses of buff, while they prevent its forward movement whereby the stresses of draft are transmitted through this key to the sills. There is no relative movement, however, between the keys 28 and the links 21 and 22, the slots 25 being but slightly larger than the key 28. The usual drawbar is shown at 29 and is provided with a slot through which the key 26 is adapted to extend.

The improved draft gear is mounted between the abutment 12 and the drawbar 29 and comprises the follower blocks 31 and 32 which are adapted to engage the drawbar 29 and the abutment 12, respectively. The blocks 31 and 32 are provided with projections or pins 30 which are adapted to engage corresponding recesses in the drawbar 29 and abutment 12 for positioning said blocks. These blocks are also provided with suitable openings through which the keys 27 and 28 extend, there being no relative movement between each key and its respective block during the operation of the gear.

The compressible portion of the gear is mounted between the blocks 31 and 32 and comprises two similar casings 33. In order that the two casings may be interchangeable they are constructed substantially alike, and each may be considered as being pro-

vided with an opening 34 extending longitudinally of the casing and with a head or abutment 35 at its inner end extending across said opening. A portion of the wall 5 of the casing adjacent to the head 35 is cut away as at 36, whereby the head or abutment 35 of each casing may be caused to enter the opening 34 of the other. The shape of the head is preferably such that it corresponds 10 with the shape of the opening. In the form shown, the opening or base 34 is circular, the casing adjacent to head 35 being semi-circular in form. The radius of the head 35 is slightly less than the radius of the inner diameter of the opening. Preferably 15 the portion or segment of the wall removed from the casings is at the side of the same whereby the overhanging portion 40 of the wall will prevent the casings when assembled, 20 from becoming disengaged by a relative vertical movement.

Suitable means for resiliently resisting the compression of the gear is mounted in the casings between the followers and the 25 heads or abutments 35 of the opposed casing. Coil springs are preferably employed for this purpose. In order to obtain the maximum amount of resistance within the minimum amount of space, the springs are 30 arranged one within the other. As shown, each casing is provided with a spring 37 of large diameter and with a spring 38 of smaller diameter within the first named spring. The springs in the forward casing 35 engage the follower block 31 which forms a closure for the opening 34 in said casing and the head or abutment 35 of the rearward casing. Likewise the springs within 40 the rearward casing engage the head 35 of the forward casing 33. In order to strengthen the heads 35 the inner faces thereof may be provided with suitable 45 strengthening ribs 39 which are integral with an apertured hub or boss 41 on the head.

When the casings and springs are assembled they may be held in interlocked position by any appropriate means. As shown, 50 a locking or positioning pin or shaft 42 is employed for this purpose. This pin extends through aligned openings through the hubs 41 of the heads. This pin extends axially into the inner springs 38 and is of sufficient length to prevent its accidental 55 removal from the hubs while in use but is of less length than the distance between the follower blocks when the gear is entirely compressed so as not to interfere with the operation of the gear.

60 It is desirable that means be provided to permit the gear to be readily removed for replacement, inspection and repair. One manner of accomplishing this is disclosed on the drawings. It consists in providing laterally extending flanges 43 at each side of the

upper portions of the casings 33. The flanges of the casings are in alinement when assembled and are adapted to engage the draft links 21 and 22, preferably the top portions thereof, whereby the gear casings 70 will be supported from said links.

In the operation of the device, assuming that there is a rearward thrust on the drawbar 29, as shown in Fig. 1, the keys 26 and 75 27 will move rearwardly in the slots but the key 28 being in engagement with the rear ends of the corresponding slots, the follower 32 cannot move any further rearwardly, hence the springs will be compressed and thereby absorb the shock. Assuming now 80 the drawbar 29 moves forwardly from the position shown in Fig. 1, the draft links 21 and 22 will move forwardly with said drawbar since they are connected to it by the key 26. The key 27 being in the forward 85 end of the corresponding slots will resist the forward movement of the follower block 31 and the draft links and key 28 will combine to move forwardly to thereby cause the follower 32 to compress the springs to cushion the movement as before.

It will be understood that various changes in the form, size, construction, composition and arrangement of the several parts may be resorted to without departing from the spirit and scope of my invention; hence I 95 do not wish to limit myself strictly to the structure herein set forth.

I claim as my invention:

1. In a draft gear, in combination, a pair 100 of casings each comprising a body having outstanding longitudinal flanges, a semi-cylindrical projection from the body portions and a plate at the outer end of the projection, the plate of each casing being entered within the projection of the other casing; a pair of followers at the outer ends of the casings; springs reacting between each follower and the plate of the more remote casing; and draft bars at the sides of the casing upon which the flanges rest.

2. As an article of manufacture, a casing 105 for use in draft gears comprising a hollow body portion, a semi-cylindrical projection from one end of the body portion, a transverse plate at the outer end of the projection and oppositely disposed longitudinal flanges on the body portion for resting upon supports.

3. As an article of manufacture, a casing 110 for use in draft gears, comprising a hollow body portion, a semi-cylindrical projection on one end of said body portion, a boss in alignment with the longitudinal axis of said body portion, means for connecting said boss to the end of said projection, and oppositely disposed longitudinally extending flanges on the upper solid portions of said casing.

4. In a draft gear, the combination of two 115 casings having interlocking projections

thereon and aligned outstanding supporting flanges, and means for holding said casings together.

5. In a draft gear, the combination of side links, followers positioned between said links, keys connecting the links and followers, interlocking casings mounted on said links and keys, and cushioning devices positioned within said casings and abutting said fol-
10 lowers.

6. In a draft gear, the combination of side links, follower blocks positioned between said links, a plurality of interlocking casings, a locking pin for connecting said casings, means on said casings for slidably supporting said casings on said links, and cushioning means within said casings for absorbing shocks. ¹⁵

In testimony whereof I affix my signature.
WALTER H. COTTON.
